HEAT TRANSFER DEVICE

Fred M. Young, Racine, Wis., assignor to Young
Radiator Company, Racine, Wis.

Application January 15, 1934, Serial No. 706,619

4 Claims. (CL. 257—154)

My invention relates to improvements in heat transfer devices commonly called radiators wherein a number of tubes, preferably in individual rows, are supplied with a multiplicity of closely spaced strip fins, the tubes terminating preferably in suitable headers having connections whereby a suitable heating or cooling liquid or gas may be caused to circulate through the tubes and whereby an air current is caused to pass around the tubes and between the fins and is heated or cooled thereby.

The object of my invention is to increase strength, and efficiency, improve appearance, reduce cost and produce a more desirable product. I accomplish these objects by means of suitably positioned and shaped embossments in the fins and novel formations in the front and rear edges of the fins whereby these edges are held in spaced relation and the air current is also suitably directed as it enters, passes through and leaves the space between the fins.

An example, embodying the preferred form of my device, has been shown in the accompanying drawing in which:

25 Figure 1 is a fractional front elevation of a radiator equipped with my improvements.

Figure 2 is a horizontal section taken on line 2 of Figure 1.

Figure 3 is an enlarged side view of a fraction 30 of a strip fin.

Figure 4 is a fractional end view of the core as shown in Figure 1.

Figure 5 is a fractional elevation of a modification.

35 My invention is applicable to any size radiator and any form of headers or connections. The form of core shown is particularly adapted for use in large units, wherein two separate core units are used, each comprising a row of tubes and

40 separate fin strips for each core. I have, however, as a matter of convenience, shown a radiator having a single row of tubes only and suitably positioned strip fins thereon. In larger units commonly called blast heaters, the cores

45 each may be two or three feet wide and from six to ten feet long. Obviously a single row of tubes having strip fins as shown will have strength and rigidity sufficient for such larger units, and also provide the desired degree of independent

50 flexibility to accommodate itself to varying degrees of temperature.

For large units it is the custom to provide two rows of tubes, each row having its own strip fins, similar to that shown in Figure 2. It will, 55 however, be understood that my device is adapt-

able to any size radiator, and that it is suitable for use with two or more rows of tubes having fins wide enough to form a single core instead of two independent cores.

It will further be understood that applicant's 60 improved device may be used without headers by supplying suitable connections between certain tube ends whereby the liquid or gas may pass through the tubes in series or series multiple for use in refrigerators and the like. 65

In the various figures the tubes are designated by the numeral 10. These tubes are supplied with the usual headers 11—11, having inlet and outlet connections 12—12. The fins 13 are supplied with suitably flanged openings 14 through 70 which the tubes extend and are bonded thereto.

Fins are made from thin copper and are therefore fragile. I provide means for stiffening the body of the fin in the form of suitably positioned embossments 15. These embossments are closely spaced and positioned to thereby register with the depression formed by the embossments on adjacent fins, thus to maintain an equal space between the fins. 75

The embossments are positioned as indicated 80 in Figure 2, wherein one is directly between the tubes, and a closely spaced row on either side as indicated in alternate position with the center embossment and the tubes. Thus it will be seen that the larger surface of the fin is occupied 85 by the tubes and embossments. The swiftly moving air will be split and deflected by the first row of embossments. This operation will be repeated by the tubes and center embossments and again by the embossments on the discharge side 90 of the core.

The air will be divided in a way into waves and turned over and over as it impinges the various surfaces at angles which will not greatly impede the air flow but will produce highly efficient heat transfer. It will be understood that the embossments may be variously shaped, that is, either cone shaped, round knobs or otherwise. 95

One of the desired conditions in radiators of this type is that the air pass through the entire surface at the same speed. This requires an even distribution of air and that it travels at right angle to the rows of tubes, the fins restricting this travel in the other direction. I provide means whereby the air will be caused to travel 100 at right angle to the rows of tubes which means is also adapted to act as spacers to the fin edges in the following manner:

The fins are necessarily very thin and fragile and therefore will not normally remain in spaced 110

relation at their edges. My improved spacers are designated in their entirety, in Figures 1 to 4, by reference character A. These spacers are formed by means of a slit of the proper length and 5 distance from the edge of the fin. The freed strip thus released is pressed preferably in the form clearly indicated in Figures 1 and 3, providing converging ends 20—20 which terminate at the apexes into a short flat section, 21 whose 10 distance from the fin is equal to one-half the distance between fins as illustrated in Figures 1 and 4.

The fins are exactly alike except that these spacers A, are formed alternately on opposite 15 sides of the fin edges and project preferably alternately on opposite sides of the fin, and the fins are assembled on the tubes whereby the apexes register with the apexes on adjacent fins, alternately as clearly illustrated in Figure 1.

20 Thus the edges will be held in spaced relation.

The spacers A, do not materially reduce the area between the fins but the side walls positioned as they are will straighten the air flow as it approaches the fins and direct it toward 25 the embossments. The spacers on the discharge side will materially assist in maintaining this desired distribution of air as it passes through the core.

The efficiency of the device will be increased 30 in that the air will impinge the diverging and alternating surfaces and a beneficial turbulence will result. The spacers A cooperating with the embossments will split the air into narrow strata which impinge the various surfaces thus 35 to reduce materially the difference in temperature between the discharged air and the fins.

Obviously the spacing members may be formed into a height equal to the distance between fins as indicated in Figure 5, and designated by 40 reference character B. These spacers B are, as illustrated, in staggered relation in regard to the assembly, but in this instance they all project in the same direction. Thus the fins are held in spaced relation and the spacers B act 45 to direct the air flow similar to spacers A. Obviously the apexes of spacers B may be pointed or round. In either event the surface which they contact is flat. However in the case of spacers A the contacting surfaces must be either 50 flat or one flat or convexed and the other any surface which will rest securely thereon.

Thus the fins are stiffened by the embossments and the edges held in spaced alignment. The air will travel therebetween at equal speed 55 and a highly efficient condition of turbulence prevail.

Obviously many minor changes in the shape of the embossments and spacers and positions thereof may be made without departing from 60 the spirit of my invention.

Having thus shown and described my invention I claim.

1. A heat transfer device comprising, a row of tubes, and means whereby a liquid or gas may circulate therethrough, a multiplicity of closely spaced strip fins through which said tubes extend, a plurality of embossments on said fins, one embossment positioned between each tube and a row on each side thereof positioned alternately with said tubes and said center embossments, a plurality of spaced apart slits cut along the front and rear edges of said fins leaving narrow strips which are formed into converging ends terminating at the apex into a short flat surface forming projections, said projections positioned alternately on opposite sides of said fins, and located whereby projections on adjacent fins register, forming alternately positioned spacers. 80 85 90

2. A heat transfer device comprising, a plurality of tubes, means whereby a liquid or gas may circulate therethrough, a multiplicity of closely spaced fins through which said tubes extend, a plurality of spaced apart slits cut along the front and rear edges of said fins leaving narrow strips which are formed into converging ends terminating at the apex into a short flat surface forming projections, said projections positioned alternately on opposite sides of said fins, and located whereby projections on adjacent fins register, forming alternately positioned spacers. 95 100 105

3. A heat transfer device comprising, a row of tubes and means whereby a liquid or gas may pass therethrough, a multiplicity of closely spaced strip fins through which said tubes extend, suitably positioned spacers between the edges of said fins having spaced apart means on the front and rear edges to direct the air current transversely between said fins, a plurality of embossments in said fins one positioned between each tube, and a row of embossments on each side thereof spaced alternately with said tubes and center embossments. 110 115

4. An air directing means for a heat transfer device having upper and lower headers and a row of tubes the ends of which are attached thereto, whereby a liquid or gas may pass from one header to the other, a multiplicity of closely spaced strip fins through which said tubes extend, comprising, a plurality of embossments on said fins, one center embossment positioned between each tube, a row of embossments on each side row of tubes and positioned alternately with said tubes and said center embossments, the projection formed by each embossment registering with the depression formed by the adjacent embossment. 120 125 130 135

CERTIFICATE OF CORRECTION.

Patent No. 1,971,842.

August 28, 1934.

FRED M. YOUNG.

It is hereby certified that error appears in the printed specification of the above numbered patent requiring correction as follows: Page 2, line 129, claim 4, after "side" insert the words of said; and that the said Letters Patent should be read with this correction therein that the same may conform to the record of the case in the Patent Office.

Signed and sealed this 30th day of October, A. D. 1934.

Leslie Frazer
